UNITED STATES PATENT OFFICE.

FREDERICK M. GODDARD AND TOIVO H. NEKTON, OF BROOKLYN, NEW YORK.

HEDGE-TRIMMER.

1,200,099.

Specification of Letters Patent.

Patented Oct. 3, 1916.

Application filed July 16, 1915. Serial No. 40,154.

To all whom it may concern:

Be it known that we, FREDERICK M. GODDARD and TOIVO H. NEKTON, citizens of the United States, and residents of Brooklyn, in the county of Kings and State of New York, have invented certain new and useful Improvements in Hedge-Trimmers, of which the following is a specification.

This invention relates to hedge trimmers and its object is to provide a portable device operated by a motor and having a knob to be used as a handle to hold the machine against the hedge to be trimmed and at the same time to be connected with the switch or valve controlling the motor to stop or start the same while the trimmer is being held in its operative position. These and other objects and details of the invention are more fully described in the following specification, set forth in the claims and illustrated in the accompanying drawings, wherein:

Figure 1, is a plan view of the improved hedge trimmer. Fig. 2 is a front view of the same. Fig. 3 is a cross sectional view on the line 3—3 of Fig. 1. Fig. 4 is a similar view on the line 4—4. Fig. 5, is a longitudinal sectional view through the line 5—5. Figs. 5 and 6, are modified forms of the trimmer. Fig. 7, illustrates a modified form of the device.

The device is designed to be held up before the operator when working and is of convenient length to fit between his extended arms when the handle 10 at one end and the knob 11 at the other end of the trimmer are each grasped by his hand. The handle 10 is located between the fork formed by the side supports 12 and the latter are attached to the end of the bar 13. The side supports 12 carry a motor 14 near their outer ends and this motor may be of the desired size to do the cutting necessary, and by means of a pinion 15 on the shaft 16 drives the gear wheel 17 carried by means of the bolt 18 from one of the supports. A wrist pin 19 on the inner face of the gear wheel 17 carries one end of a pitman 20 whose other end is pivoted to a rod 21 extending along the bar on its upper side and adapted to be reciprocated by the pitman.

The lower side of the bar 13 is chamfered and a steel bearing plate 22 set into the upper face thereof, while on the under surface of the bar is secured a stationary blade 23. In the space between the plate 22 and

the blade 23 is placed a movable blade 24, the two blades having corresponding cutting teeth projecting beyond the edge of the bar 13. Ordinary wood screws may be employed to secure the plate 22 and the blade 23 to the bar and connecting blocks 25 interposed between the bar 21 and the moving blade and secured to them by bolts, are adapted to play in slots 26 so that means are thus provided for the movement of the latter blade. The blade 23 is also provided with angle pieces 27 at each end of the bar to prevent it from being injured and bent out of its proper shape.

The knob 11 is of non-conductive material and mounted on a pivot 28 passing through the bar and having the nuts 29 to retain it in place, while on the lower side of the knob is a small disk 30 having contact pin 31 extending downward. The disk 30 is located in a socket 32 and in the bottom of which is a flat contact spring 33 connected to one end of an electric circuit 34 including a source of energy, the motor 14 and the pin 31.

In operating this device the handle is grasped by one hand, preferably the left, and the knob 11 is held in the other hand so that when it is desired to start work the knob is turned to close the circuit 34 by the contacts 31 and 32 and the motor operates the gear wheel 17, reciprocating the cutter blade 24. The trimmer may be moved over the top and sides of the hedge, cutting the outer branches to the desired depth and insuring uniformity on account of the length of the bar.

It is obvious that a hedge trimmer constructed on this plan may be operated with other motive means than electricity as above described and where compressed air, gas or steam is used the knob 11 may be otherwise employed such as to control the sparkler of a gas engine or the valve of a fluid motor to open and close the latter to operate the device while holding it in position to do its work.

The modified construction shown in Fig. 6 employs a gas engine 35 mounted between the supports 12 and carries on its shaft 36 the crank disk 37 to operate the connecting rod 38 and drive the cutting blade as described above. In this instance the knob 11 controls the sparkler circuit 39.

In Fig. 7 a circular cutting blade 40 is used and located on the under side of the

bar 13 being protected by a plate 41, while the electric motor 42 is carried on the upper side of the bar and connected with the blade and driven by the gearing 43.

5 The parts may be otherwise arranged or modified without departing from the essential features above described or from the scope of the appended claims.

What we claim as new is:

10 1. In a hedge trimmer, the combination with a bar, adapted to be held between the outstretched hands of the operator, of rod extensions at one end of the bar and connected by a handle, a stationary blade at one side of the bar, a moving blade adjacent to the first blade, a motor for the latter blade carried between the extensions, and a handle at the other end of the bar and adapted to control the motor.

15 2. In a hedge trimmer, the combination with a bar having handles at each end, of a motor at one of the handles, controlling means for the motor at the other handle, a

blade on the front edge of the bar, and a cutting blade moving adjacent to the same 25 and operated by the motor.

3. In a hedge trimmer, the combination with a bar having a depression at one edge and a slot, of a stationary blade in the depression, a moving blade adjacent to the 30 stationary blade, a handle at one end of the bar, a motor at the handle, a handle at the other end of the bar, a controller for the motor operated by the latter, connecting means between the controller and the motor, 35 gearing on the motor, a pitman operated by the gearing, and studs from the moving blade extending through the slot in the bar and connected with the pitman.

Signed at Brooklyn, in the county of 40 Kings, and State of New York, this 29th day of May, A. D. 1915.

FREDERICK M. GODDARD.
TOIVO H. NEKTON.
